Primary Examiner — Kelley Donnelly*(74) Attorney, Agent, or Firm* — Bereskin & Parr LLP/S.E.N.C.R.L., s.r.l.(57) **CLAIM**

The ornamental design for a display rack for paint chips, as shown and described.

DESCRIPTION

FIG. 1 is a front perspective view of a first embodiment of the display rack for paint chips;

FIG. 2 is a front elevation view thereof;

FIG. 3 is a side elevation view thereof; the other side being identical;

FIG. 4 is a front perspective view of a second embodiment of the display rack for paint chips;

FIG. 5 is a front elevation view thereof; and,

FIG. 6 is a side elevation view thereof; the other side being identical.

The broken lines showing is included for the purpose of illustrating environment of the design and forms no part of the claimed design.
